UNITED STATES PATENT OFFICE

2,306,043

SUN ROCKER

William Dane, Elmont, N. Y.

Application September 6, 1940, Serial No. 355,693

2 Claims. (Cl. 155—69)

This invention relates to improvements in sun chairs, and more particularly to rocking chairs in which an individual may secure the benefits of sun or other radiant energy treatment.

An object of this invention is to provide a device to amuse or exercise the user or patient during the actinic ray treatment.

Another object is to provide a safe, freely movable rocker which enables the exposure of the patient's body to health promoting rays.

A further object of this invention is to provide a chair permitting controlled exposure of the patient's uncovered body.

Other objects and advantages of the invention will be apparent during the course of the following description.

In the drawing:

Figure 1 is a side elevation of a rocker embodying my invention,

Figure 2 is a plan view of the rocker, and

Figure 3 is a central vertical longitudinal section taken on the line 3—3 of Figure 2.

Referring now to the drawing in detail, numeral 4 denotes curved or semi-circular rockers firmly interconnected by crosspieces 5 to constitute the base of the chair. A suitable seat 6 is supported by vertical uprights 7 which are centrally located between the ends of the rockers. Convenient fasteners such as screws 8 may be used to secure uprights 7 to rockers 4.

Uprights 7 are provided on their external sides with eyelets or hooks 9 to accommodate rods 10. Rods 10 are preferably of pipe having sufficient length to extend above the user's head. Arcuate rods 11 have their upper end portions 12 conditioned to fit snugly in the upper end of pipe sections 10. The lower ends 13 of rods 11 firmly yet removably engage depressions in the rear ends of rockers 4. An adjustable canopy 14 of fabric or other suitable material is attached to supporting rods 11 and is conditioned to be slid to any desired position.

Numerals 15 represents a foot rest positioned an appropriate distance in front of the seat uprights 7 and spans the gap between the two substantially parallel rockers 4. Any well known means will serve to bind these members.

Uprights 7 extend above seat 6. Near the top of the upright is attached a U shaped hand grip 16. This grip is fastened at 17 by convenient means so as to prevent rotation about these points and extends forwardly of the seat 6 presenting a hand bar 18 within comfortable reach of its occupier.

The operation of the chair is as follows:

The awning 14 is slid along supporting rods 11 to a position near the bend 12 at the top of the rods. Since there is no crosspiece at the upper rear of the rocker the patient or user has convenient access to the seat 6 by approaching from the rear. By stepping over the seat 6 and grasping the hand bar 18, the user may take a comfortable seated position with his feet propped on the footrest 15. In the well known manner the user may shift his weight and manipulate the rocker to his satisfaction or it may be guided by an attendant. The backless seat permits the desired rays to reach the dorsal region of the patient and yet safety is assured by the convenience of the hand grip.

The canopy 14 may be extended to shield the patient from the rays of the sun after the desired time exposure has been attained. Thus the patient can then safely use the apparatus for enjoyment or mild exercise without the danger of over exposure. If desired, the awning may be dispensed with by sliding into a compact mass or by removing its supporting members from the rocker entirely. The eyelets 9 for rods 10 and the telescopic fit of arcuate rods 11 in the depressions in rockers 4 at 13 permit ready removal of the awning structure when it is not desired.

The arcuate rockers 4 with their small points 30 of contact with the ground, permit easy shifting of the chair about a vertical axis to follow the course of the sun so that a most effective exposure may be given to a selected portion of the body. Likewise, with a minimum of exertion the operator or attendant may shift the rocker to expose new sections of the epidermis to the sun.

The crosspieces 5 and the large arcuate rockers permit any easy manipulation of the chair and provide the minimum possibility of upsets.

It is to be understood that the form of this invention, herewith shown and described, is to be taken as a preferred example of the same, and that various changes in the shape, size, and arrangement of parts may be resorted to without departing from the spirit of my invention, or the scope of the subjoined claims.

Having thus described my invention, I claim:

1. In a device of the character described, rockable base means comprising two spaced rockers 50 adapted for rocking movement in a forward and backward direction only, a backless seat disposed substantially laterally of said rockers and being supported thereby, two canopy frame rods extending upwardly from said seat on opposite sides thereof and rearwardly joining with said rock-

ers, and a canopy extending between said canopy frame rods and being slidably mounted thereon.

2. In a device of the character described, rockable base means comprising two spaced rockers adapted for rocking movement in a forward and backward direction only, two substantially opposite uprights mounted on said rockers and sup-

porting a backless seat and a handgrip, two canopy frame rods extending upwardly from said seat on opposite sides thereof and rearwardly joining with said rockers, and a canopy extending between said canopy frame rods and being slidably mounted thereon.

WILLIAM DANE.
